CLAIM

The ornamental design for an outboard cowling, as shown and described.

DESCRIPTION

FIG. 1 is a perspective view of an outboard cowling in accordance with the present invention.

FIG. 2 is a right side view of the outboard cowling shown in FIG. 1, the left side view being a mirror image thereof. FIG. 3 is a rear view of the outboard cowling shown in FIG. 1.

FIG. 4 is a front view of the outboard cowling shown in FIG. 1; and,

FIG. 5 is a top view of the outboard cowling shown in FIG. 1.

The broken lines shown throughout the drawing views are for illustrative purposes only and form no part of the claim design.
